Edwards, Sager & Bower.

UNITED STATES PATENT OFFICE.

FREDERIC H. BULLINGER, OF YONKERS, NEW YORK, ASSIGNOR TO WARD LEONARD ELECTRIC COMPANY, A CORPORATION OF NEW YORK.

DYNAMO REGULATOR.

Application filed December 17, 1920. Serial No. 431,322.

To all whom it may concern:

Be it known that I, FREDERIC H. BULLINGER, a citizen of the United States, residing at Yonkers, in the county of Westchester and State of New York, have invented certain new and useful Improvements in Dynamo Regulators, of which the following is a specification.

This invention relates to dynamos driven from a variable speed source, such as the gas engine of an automobile, and to means for regulating and controlling the charging current supplied by the dynamo to the storage battery and to lamps and other translating devices connected to the battery and dynamo circuit.

One object of the invention is to combine the regulator with the dynamo to form a unitary and self contained construction. It thus produces a simplified unit with the regulating means enclosed within the dynamo frame and thus protected from dust and dirt and is also protected from mechanical injury. Another object is to produce a small and efficient regulator and to make use of sheet metal parts as far as possible in the construction of the regulator, to avoid as far as possible the use of rivets, and also to avoid the necessity of refined

adjustments in the assembly of the device. Another object is to produce a simplified construction and relationship of parts, which may be economically manufactured and assembled. These and other objects and advantages of my invention will be understood from the following description and accompanying drawings, which illustrate a preferred embodiment of my invention.

Fig. 1 is a sectional view of a portion of a dynamo showing the union of a regulator therewith and showing a plan view of the regulator. Fig. 2 is a front elevation of the regulator and brush frame removed from the dynamo. Fig. 3 is a plan view of a portion of the regulator with the cover of certain parts removed. Fig. 4 is a rear view of a portion of the regulator with the cover removed. Fig. 5 is a development of one of the parts, and Fig. 6 is a diagram of connections.

Referring to Fig. 1, the dynamo armature 1 is indicated, having a commutator 2 and a removable end frame 3. This frame

55 is shown as carrying the bearing 4 for one

end of the armature shaft 5, and also carries a circular brush frame 6. The frame 6 has a flange 7 by which it is secured to the frame 3 by screws 8. The brush frame is angularly adjustable for properly positioning the brushes, the screws 8 passing through slots or cut-away portions in the flange 7 and engaging a clamp or ring within the flange 7, which serves to hold the brush frame in any desired angular position, an adjustable mounting being usual in dynamo construction. In this particular instance, a four pole dynamo is contemplated having two brushes 9, 9, spaced angularly 90° apart, the brush holders 10 being mounted upon the brush ring 6. Each brush holder has a projecting lug 10^a with a screw 10^b to form a terminal connection. The springs 11 for the brushes are shown mounted on lugs extending from the brush holders and extending through cut-away portions in the brush holders for engaging the outer ends of the brushes.

The upper brush holder is insulated from the brush ring by sheets 12 of insulating material, which are circular in shape and also serve to insulate the regulator frame from the brush ring. The main frame of the regulator consists of a sheet metal piece of non-magnetic material bent at right angles and having one portion 13^a in a plane perpendicular to the axis of the dynamo shaft and another portion 13^b at right angles to the other portion.

An extension 13^c extends from the portion 13^b of the frame, and engages the lug 10^a of the upper brush holder being secured thereto by the screw 10^b. The part 13^c thus serves as an electrical connection between the brush holder and the regulator frame as well as a support therefor. The portion 13^b of the frame also has another extension 13^d bent at right angles thereto and extending parallel to the brush ring to which it is suitably mechanically secured, but electrically insulated therefrom. The extension 13^d also has supported thereon a tubular resistance unit 14, which in this instance is placed endwise on the extension and serves to form the comparatively high field resistance for varying the field strength of the dynamo as controlled by the action of the regulator.

The magnet of the regulator has an E-shaped sheet metal stamping 15 of soft iron

- mounted perpendicularly to the plane of the portion 13^a of the frame and extending inwardly over the commutator of the dynamo as shown in Fig. 1. The three ends of this stamping extend through three slots in the portion 13^a of the frame, and the two outer legs of the stamping have cut away shoulders at their ends to seat against the face of the portion 13^a and have their ends headed over on the opposite side of the portion 13^c to secure the same firmly thereto. The middle leg of the stamping carries a coil 16, one end of which is electrically connected to the stamping 15 and through it to the frame of the regulator and by the extension 13^c to the upper brush holder. The stamping 15 has mechanically supported thereon but insulated therefrom, a stamping 17 which has a projecting lug and screw 17^a to form a terminal. The other end of coil 16 is electrically connected to this terminal.
- On the opposite side from the magnet of the portion 13^a of the main frame is the pivotally mounted vibratory armature 18 of sheet metal. This is pivotally mounted by means of a phosphor bronze strip 19, which is clamped to one end of the armature by means of a sheet metal piece 20 having a tongue 20^a on each edge which is bent over the strip 19 and armature 18 through side notches therein, thus clamping the parts together in a fixed position. A fixed support for the other end of the strip 19 is formed by a pair of sheet metal blocks 21 notched on opposite sides as shown in Fig. 4 on which is located one end of the strip 19. The parts are clamped to the portion 13^a of the main frame by another sheet metal block 22 having tongues 22^a on opposite sides to engage the notches in the pieces 21 and which also pass through slots in the portion 13^a and are bent over on the opposite side of the portion 13^a, thus clamping these parts in fixed position.
- The opposite end of the armature carries a contact 18^a adapted to make and break the circuit with the fixed contact 23. The latter is carried by a sheet metal piece 24 secured to the portion 13^a of the frame, but electrically insulated therefrom. The piece 24 has two right angle bends as shown in Fig. 3 so as to bring the fixed contact 23 in proper position with relation to the vibratory contact 18^a.
- A spring 25 tends to normally hold the contact 18^a against the fixed contact. This spring is in the form of a wire having a hook on one end by which it is secured to the movable end of the armature by being passed through two holes as shown in Figs. 3 and 4. The spring 25 passes over a fulcrum 22^b, which is formed by bending a portion of the sheet metal piece 22 at right angles, the outer edge having a notch therein to receive the spring. From the fulcrum the spring ex-

tends under a hook 22^c, which is also integral with the sheet metal piece 22, the hook being stamped out with the other parts of the sheet metal piece 22 and afterwards bent at about right angles thereto to form a fixed support for one end of the spring. The development of piece 22 is shown in Fig. 5. The fixed end of the spring 25 is bent outwardly as shown in Fig. 3 where it passes under the hook 22^c. The portion 22^c may be bent more or less by pliers or otherwise at or near its base so as to vary or adjust the tension exerted on the spring 25. Thus if the portion 22^c be bent toward the plane of its base it will draw the end of the spring nearer to the base and thus exert a greater tension tending to hold the contacts closed, whereas bending the portion 22^c towards a position perpendicular to its base will lessen the tension on the spring. In this manner quick and permanent adjustment of the spring tension may be readily and conveniently obtained. The fulcrum 22^b may similarly be bent if desired for adjusting the spring tension.

Also secured to the portion 13^a of the main frame and on the opposite side from the sheet metal piece 24 is another sheet metal piece 26. This has the bent portion 26^a facing the part 13^a, but insulated therefrom and electrically connected to the strip 24 by the attaching rivets 26^b. Piece 26 has an extension 26^c with a screw 26^d to form a terminal connection. It also has another extension 26^e which extends over the resistance unit 14 and has a tongue extending downwardly within the resistance tube for the purpose of holding the resistance tube in position.

The operating parts of the regulator are enclosed by the portions 13^a and 13^b of the regulator frame together with a removable sheet metal cover. This cover is stamped from sheet metal and bent to form a top cover portion 29, which is slotted near one edge to receive a projection 13^e from the portion 13^a of the frame, serving to thus position the cover piece. The cover piece has a downwardly extending side portion with a projection extending into the slot 13^f in the part 13^b of the main frame. The cover piece also has enclosing end portions with extensions which project through the slots 13^g also in the portion 13^b of the main frame, the projections from the cover piece passing through these slots being adapted to be bent over on the lower side of the part 13^b to hold the cover piece in place or to be otherwise secured, as by the manufacturer's seal to prevent unauthorized tampering or adjustment of the regulator.

The circuits and electrical connections of the parts will be understood from Fig. 6. The dynamo is indicated at 1 having the two brushes 9 and a shunt field winding 27. The upper brush 9 is electrically connected to the

main frame of the regulator and to the iron part 15 of the magnet, from which the circuit continues through the series coil 16 to the leads and suitable switches to the battery 5 28 and other translating devices in parallel, from which the circuit is completed back to the lower brush 9. The field winding is connected from the lower brush 9 to the terminal connection 26^e and thence, by the construction already described, the circuit is continued through the sheet metal pieces 26 and 24 to the fixed contact 23; thence the circuit continues through the movable contact and vibratory armature to the main 10 15 frame of the regulator and to the upper brush 9. The resistance 14 is thus normally shunted by the regulator contacts, one lead from the resistance being connected to terminal 26^e and the other lead to the main 20 frame.

In operation with the dynamo being driven at a suitable speed and the charging circuit to the battery closed through the usual cutout switch, the parts will remain 25 in the position shown until the charging current attains a predetermined maximum value, at which time the armature 18 will be attracted by the magnet, breaking the shunt around the resistance 14, at the regulator contacts. This throws the resistance 14 into the field circuit, causing the charging current to be reduced to a predetermined minimum, at which time the spring 25 overcomes the attractive force of the magnet and 30 35 closes the circuit at the regulator contacts. This short circuits the resistance 14 and causes the voltage of the dynamo and the charging current to be increased to the predetermined maximum value. This cycle of 40 operations is continued as long as the speed of the dynamo is sufficient to cause the predetermined maximum charging current to be attained with the regulator contacts closed. The battery is thus protected from excessive 45 charging current by the vibratory action of the regulator.

Although I have illustrated and described in detail one embodiment of my invention, it will be understood that various modifications 50 may be made and that my invention may be exemplified in various embodiments, without departing from the scope of the invention,

I claim:—

55 1. The combination of a dynamo and an electric circuit controller for controlling the output of said dynamo, said controller comprising a frame carried by the brush frame of the dynamo, said controller frame having a portion thereof contacting with and in direct electrical connection with a brush holder of one of the dynamo brushes, said frame also forming a terminal of said controller.

60 2. The combination of a dynamo having

a brush frame, and an electric circuit controller for controlling the output of the dynamo carried by said frame, said controller comprising an electro-magnet having a controlling coil extending over the commutator 70 of the dynamo with its axis parallel with the axis of the dynamo.

3. The combination of a dynamo having a brush frame, and an electric circuit controller for controlling the output of the dynamo carried by said frame, said controller comprising an electro-magnet having a controlling coil extending over the commutator of the dynamo with its axis 75 parallel with the axis of the dynamo, and 80 said controller having a frame directly engaging and in electrical contact with and supported by a brush holder of one of the dynamo brushes.

4. The combination of a dynamo, and an 85 electric controller for controlling the output of the dynamo, said controller comprising a frame carried by the brush frame of the dynamo, contact controlling means on one side of said controller frame, and an 90 electro-magnetic winding on the opposite side of said controller frame and extending over the commutator of the dynamo.

5. The combination of a dynamo, and an 95 electric circuit controller for controlling the output of the dynamo, said controller comprising a frame carried by the brush frame of the dynamo, said controller frame having a sheet metal portion extending at right angles to the axis of the dynamo, and an 100 electro-magnet supported on said portion of the controller frame and extending over the commutator of the dynamo.

6. The combination of a dynamo, and an 105 electric circuit controller for controlling the output of the dynamo, said controller comprising a frame carried by the brush frame of the dynamo, said controller frame having a sheet metal portion extending at right angles to the axis of the dynamo, an electro-magnet supported on said portion of the controller frame and extending over the 110 commutator of the dynamo, and contact controlling means on the opposite side of said portion of said controller frame.

7. The combination of a dynamo, and an 115 electric circuit controller for controlling the output of the dynamo, said controller comprising a frame carried by the brush frame of the dynamo, said controller frame having a portion extending at right angles to the axis of the dynamo, an electro-magnet supported on said portion of the controller frame and extending over the commutator 120 of the dynamo, said controller frame directly engaging and in electrical contact with a brush holder of one of the brushes of the dynamo, and said controller frame also forming a terminal of said controller.

8. The combination of a dynamo, and an 130

4
electric circuit controller for controlling the output of the dynamo, said controller comprising a frame carried by the brush frame of the dynamo, electro-magnetic controlling means carried by said controller frame, a controlling resistance unit carried by the brush frame, and an insulated terminal carried by said controller frame for positioning said resistance unit and forming one terminal of said unit.

9. The combination of a dynamo, and an electric circuit controller for controlling the output of the dynamo, said controller com-

prising a frame carried by the brush frame of the dynamo, electro-magnetic controlling means carried by said controller frame, a controlling resistance unit carried by the brush frame, an insulated terminal carried by said controller frame for positioning said resistance unit and forming one terminal of said unit, and said controller frame forming a terminal of said controller and also forming a terminal of one of the brushes of the dynamo.

FREDERIC H. BULLINGER.
